ADJUSTABLE TABLE

Edward F. Lundein, Rock Island, Ill.

Application June 22, 1934, Serial No. 731,906

18 Claims. (Cl. 128—72)

The present invention relates to adjustable tables and more particularly to that class of tables commonly referred to as chiropractic tables. Among the objects of this invention are to provide, in a table of the character indicated, improved means for raising the tilting body of the table relatively to the base; to provide mechanism whereby the body of the table is pushed into an elevated position, instead of being pulled into such position; to provide improved mechanism for longitudinally adjusting one or more of the cushions with relation to the frame by which they are carried; to provide improved means for varying the spring tension by means of which the table body is raised; to provide improved means for adjusting the inclination of one or more of the cushions of the table; to provide improved means for supporting one or more of the table cushions; and such further objects, advantages and capabilities as will hereafter appear and as are inherent in the construction disclosed herein. My invention further resides in the combination, construction and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 is a side elevation of a table embodying my present invention;

Fig. 2 is a longitudinal section of the structure shown in Fig. 1, taken approximately centrally of the table;

Fig. 3 is a fragmentary sectional elevation taken approximately along the broken line 3—3, Fig. 4;

Fig. 4 is a sectional plan taken approximately along the plane indicated by the line 4—4, Fig. 3;

Fig. 5 is a fragmentary plan section at one end of the table body, taken just above the frame thereof;

Fig. 6 is a fragmentary sectional elevation showing a cushion adjustment latching means;

Fig. 7 is a fragmentary plan view of a cushion adjustment latching means, on a somewhat larger scale than shown in Fig. 5;

Fig. 8 is a fragmentary longitudinal horizontal section through an end portion of the table body frame.

Reference will now be made in greater detail to the annexed drawings for a complete description of the structure embodying my present invention.

This structure comprises a base having legs 1 and

2, and side rails 3, and a pivoted, tilting body having side rails 4, connecting elements 5 whereby the rails 4 are connected to the legs 2, and a plurality of cushions 6, 7, 8 and 9. The support 10 upon which the patient stands when the table is in elevated position is pivotally connected to bracket arms 11 extending from the connecting means 5. A lug 12 is located approximately centrally of the support 10 and furnishes means for attachment of the links 13 connected to the push rod or link 14 whereby the table body is raised. A bolt 15 passes transversely of the frame through the upper portion of the connectors 5 and has mounted thereon, adjacent the connectors 5, the brackets 16, whereby the leg cushion 9 is supported, at one end, upon the body frame. Spacing the brackets 16 from the push rod 14 are sleeves 17, one upon each side of the rod 14. It will thus be seen that this rod is always held in proper position with relation to the connectors 5 and brackets 16.

A supporting bolt or rod 18 connects the two brackets 16 and serves as means for supporting the ends of the bail-shaped latching means 19. The central part of this bail-shaped latching means serves as a handle for operating said means which is provided with notches 20 for engagement with a rod or bolt 21 which connects similar supporting means 22 upon opposite sides of the table. Each supporting means 22 comprises a pair of links pivotally connected by the rod 21 and having their free ends connected at 23 and 24 with frame members 4 and angle irons 25, respectively. At one end, the cushion 9 has guides 26 which slide along the angle irons 25, thus holding the cushion 9 positioned laterally with relation to the frame of the table body. At its middle portion, the cushion 9 has other guiding members 27 provided with thumb-screws for engagement with the angle irons 25 to guide the cushion and secure it in adjusted position. By loosening these thumb-screws, the cushion 9 can be moved longitudinally of the angle irons and, when a proper adjustment is secured, the thumb-screws will be tightened up to hold the cushion in adjusted position. In order to adjust the inclination of this cushion, the latch 19 is raised until the rod 21 is released from a notch 20 and then the cushion is raised or lowered until the proper inclination is secured when the latch will be lowered until the appropriate notch 20 engages rod 21. This will insure that the cushion 9 will be held in adjusted position.

The side members 3 of the base have inwardly projecting flanges 30 for engagement by the slide

31 which has downwardly and outwardly projecting lugs 32 engaging under the flanges 30. Thus the slide 31 is held to the side members 3 and is capable of sliding along the same as the 5 table body is raised or lowered. Between the lugs 33 on the edge of the plate 31 is the free end of the push rod 14, the lugs 33 and rod 14 being pivotally secured together by means of the bolt 34. The main table operating springs 35 are 10 secured at one end to the cross piece 36 at one end of the base and at their other ends they are secured to lugs 32a projecting downwardly from the plate 31. It will thus be seen that one end of each of these springs is rigidly connected 15 to the base of the machine and the other end to the slide 31 which is connected through the link or push rod 14 to the tilting body of the table. Therefore, when the table body is released from its position shown in Figs. 1 and 2 and permitted 20 to rise toward the position shown in Fig. 3, the springs 35 contract, pulling the slide 31 and pushing the push rod 14 so as to push the table toward upright position, the connectors 5 turning on their pivots 37. When the table body is pulled downward 25 toward the position shown in Figs. 1 and 2, the springs are expanded and put under tension. Attention is called to the fact that there is no adjustment of the tension of these springs other than that caused by the raising and lowering of 30 the table body.

In the side rails 4 of the table body are longitudinal slots 40 in which are slidable certain brackets 41 which support a frame 42 carrying the cushion 8. This cushion is connected to the 35 frame by means of the cross levers 43 and 44, pivotally connected by the rod 45. This cushion is pivotally connected directly to the levers 44, as shown in Fig. 2, and indirectly connected, by means of the links 46, to the free ends of the levers 40 43. The lower ends of the levers 44 are connected to a cross bar 47 which rests and slides on the sides of the frame 42. Brackets are secured to the ends of the cross bar 47 and extend under the side members of the frame 42 to insure that 45 the cross bar 47 will be held in slidable relation to the frame. Connected to this cross bar 47 are springs 48 which are connected at their opposite ends to a cross bar 49 secured to the frame 42. It will thus be seen that the cross bar 50 47 may move toward and away from the nearer end 50 of the frame 42, being actuated away therefrom by the springs 48. This tends to raise the cushion 8 to the upper limit of its motion. A notched latch lever 51 is pivotally mounted 55 upon the end member 50 of the frame 42 and may be turned into position so that one of the notches thereof will engage the pin 52 on the cross bar 47. In this way depression of the cushion 8 may be prevented, when desired. Since the pivot 60 at the lower end of levers 43 is fixed with relation to the frame 42, it is necessary for cross member 47 to move toward end member 50 in order that the cushion may be depressed. The pivot 45 therefore moves in an arc of a circle about the 65 fixed pivot at the lower end of levers 43. Likewise, cushion 8 moves slightly toward cushion 9 during its motion of depression.

It is customary and practically necessary to 70 have the cushions 6, 7, 8 and 9 relatively adjustable with relation to each other and the body frame and provision is made, therefore, for adjusting the cushions 6, 7 and 8, as well as the cushion 9. As indicated above, there are brackets 75 41 secured to the frame 42 which extend into the slots 40 in members 4 to support the frame 42

and permit the same to slide longitudinally of the body frame members 4. The means for adjusting the frame 42 and the supported cushion 8 will next be described. A rack bar 55 is secured to the end member 56 of the body frame and extends longitudinally thereof, substantially centrally, with relation to the side bars. This rack bar has teeth in its upper surface and these are engaged by a gear 57 carried by a shaft 58 mounted in the support 59. The shaft 58 has handles 60 at its opposite ends whereby it may be rotated to cause rotation of the gear 57 and movement thereof along the rack 55. An angular frame 61 has openings therein through which the shaft 58 passes, as indicated at 62 10 and 63. The frame 61 is therefore slidable longitudinally of the shaft 58 but is normally held in the position shown in Figs. 5 and 7 by means of the spring 64. A projection 65 extends inwardly toward the gear 57, as indicated in Figs. 15 6 and 7, and engages between the teeth of the gear 57 when member 61 is left free to move under the influence of the spring 64. In this way, the gear 57 is latched against rotation and the frame 42 is held in adjusted position until 20 the spring 64 is compressed sufficiently to release the gear 57 from the projection 65.

An identical construction, except that the latching means 65 is on the opposite edge of the frame 61, is made use of to hold the slide 66 in 30 place. This slide carries the cushions 6 and 7 upon the uprights 67. The shaft 58 for this slide passes through openings in the uprights 67 and it will therefore be seen that rotation of the shaft 58 and rack gear 57 will cause movement 35 of the uprights 67 and slide 66 longitudinally of the side bars 4. As indicated in Fig. 8, the uprights 67 have feet 68 which extend out almost into contact with the bars 4, thereby preventing any substantial sideway movement of the 40 slide 66. This slide extends to the inner surfaces of the walls of bars 4 and the slide is therefore held in the slots 69 which are comparable to the slots 40, described above. The slide 66 moves freely under the influence of the springs 71 and 45 the rack and pinion mechanism described above. A cross bar 72 extends through the slots 69 and nearly across the tubular members 4, as shown in Fig. 8. This cross bar 72 is notched in its 50 opposite ends for engagement by the ends of the springs 71 which thereby put tension upon the slide 66 to pull it toward the end of the body frame. To move this slide in the opposite direction, the latch 65 is released from the gear 57 and a handle 60 is turned to cause the gear to 55 travel along the rack, thus moving the slide and extending the springs 71.

As is usual, the head cushion 6 is divided into two parts which are laterally movable relatively to each other by means of the lever 72. This being usual construction, no further attention need be paid thereto. A bail-shaped frame 73 has pivotal connection with the upper portion of the uprights 67 and supports the cushion 6 for pivotal movement about its pivots 74. The angle of inclination of this cushion may be adjusted in the same manner as that of cushion 9 or in any other of several other ways but I prefer to use the same adjustment for this as is used in adjusting the cushions 6, 7 and 8 longitudinally of the frame. In view of the detailed description of this in connection with the longitudinal adjustment of these cushions, it does not appear to be necessary to describe this structure specifically.

Approximately centrally of one edge of the plate 31 and projecting downwardly therefrom are a pair of lugs 75 which serve as lateral guides for the bar 76 which has notches 77 in the upper edge thereof, as shown in Fig. 2. These lugs 75 have a short cross bar 78 connecting them and upon which the bar 76 slides. These parts 75 and 78 hold the bar 76 in proper position and guide the same during operation of the table. At its other end, the bar 76 has a cross bar 79 which is notched at its two ends to embrace the flange 30 of the side rail 3. This therefore serves as a guide for the free end of this bar. A pawl 80 is pivoted at 81, where it is connected to the plate 31. This pawl has a nose 82 which engages with the notches 77 when not restrained from doing so. Upon one side of the pawl 80 is a curved bracket 83 which extends laterally, as shown in Fig. 4, to ride on a rod 84 which is slidably mounted in downwardly extending flanges of the plate 31. The end of this rod is turned laterally, as shown in Fig. 4, and may rest in any one of several notches 86 formed in the upper edge of a depending bracket 87. A weight 88 serves also as a handle by means of which the end of the rod may be manipulated to vary the position of the angle 89 which is engaged by the bracket 83 as the latter is reciprocated by reciprocation of the plate 31.

When the table body is lowered from the elevated position indicated in Fig. 3, the link 14, as indicated above, moves longitudinally of the base, pushing the plate 31 ahead of it. To the forward edge of this plate is connected the pawl 80 and this, therefore, also moves longitudinally of the base. In Fig. 4, the angle 89 of the rod 84 is shown in its middle position of adjustment. Therefore, when the bracket 83 passes the angle 89, there is nothing to prevent the nose 82 of the pawl 80 from dropping into a notch 77 of member 76. From this point on, in the travel of the plate 31, member 76 is caused to travel with plate 31. A cross plate 91, at the rearward end of bar 76, furnishes means for the attachment of the auxiliary springs 92 which have their opposite ends connected to the cross member 36, forming a part of the base, as indicated above. Therefore, when the nose 82 drops into the notches 77, all four springs 35 and 92 are active in pushing the table body toward raised position. A pair of plates 93, upon opposite sides of pawl 80, serve to keep this pawl substantially in perfect alignment above member 76. The farther to the right the handle 88 is moved, the sooner the pawl 80 engages the rack 76 and the sooner will the auxiliary springs come into operation to assist in raising the weight of the table and patient. On the contrary, the farther the handle 88 is moved to the left, as seen in Fig. 3, the longer will it be before the pawl 80 becomes effective to bring the auxiliary springs 92 into operation.

When the table body is brought down into the position shown in Figs. 1 and 2, a plate 95, carried by the side rails 4, is engaged by the dogs 96, pivoted at 97. Springs 98 normally hold these dogs in latching position, from which they are moved by a shaft 99 carrying projections in position to engage the dogs so as to disengage them from the plate 95. Pedals 100, when pushed downwardly, cause rotation of the shaft 99 and disconnection of the dogs 96 from the plate 95.

It will of course be understood that the specific description of structure set forth herein may be departed from without departing from the spirit

of this invention as set forth in the foregoing specification and in the appended claims.

I claim:

1. In a table of the character described, a frame comprising longitudinal frame members and a transverse member connecting them at one end, rigidly, a rack connected to said transverse member and extending longitudinally of the frame substantially parallel with said longitudinal frame members, a pair of cushions having supporting means carried by said longitudinal frame members, pinions carried by said cushion supporting means and cooperating with said rack in adjusting the cushion supporting means and the cushions longitudinally of the frame.

2. A table of the character described having a body frame comprising a pair of longitudinally extending side rails slotted on their sides facing each other, cushion supports extending into said slots to support the cushions relatively to the frame, a rack connected to the frame and extending longitudinally thereof and in proximity to said cushion supports, shafts carried by said cushion supports and extending transversely of said frame and the rack, pinions carried by said shafts in cooperative relation with said rack and serving, when the shafts are rotated, to adjust the cushion supports longitudinally of the frame.

3. A table having a cushion supporting frame comprising a pair of substantially parallel longitudinally extending side members having slots in the portions facing each other and extending longitudinally of the side members, and a cushion support having a part extending into said slots which serve as guiding means to assure a definite direction of movement of the cushion with relation to the frame.

4. A structure as defined by claim 3 having spring means for biasing the cushion in one direction and operating means for moving it in the opposite direction.

5. A structure as defined by claim 3 having spring means within the side members tending normally to cause movement of the cushion in one direction and rack and pinion means for causing movement of the cushion in the opposite direction.

6. A table for the purpose indicated comprising a cushion supporting frame having a pair of tubular substantially parallel longitudinally extending side members provided in their sides facing each other with longitudinally extending slots for the reception of cushion supporting means, means for supporting cushions upon said frame extending into and slidably in said slots, and means for actuating the cushion supports in opposite directions.

7. A structure as defined by claim 6 in which the cushion actuating means comprises rack and pinion mechanism for causing relative movement between the cushion supporting frame and the cushion supporting means in combination with latching means supported for movement transversely of the pinion to engage or disengage the same for the purpose of holding the cushion in adjusted position or permitting adjustment thereof.

8. A table comprising a base and a body, said base having legs, said body having connectors at one end whereby the body may be connected to the base, pivotal connecting means pivotally connecting said connectors to said legs near their lower ends, a push rod connected to said connectors remote from said pivotal connection,

- spring means normally pulling on said push rod to push the body toward elevated position when released for upward swinging motion, and body supporting cushions supported on the said table body.
9. A structure as defined by claim 8 having a slide connected to the base and slidable therealong, said push rod and said springs being connected to said slide.
10. A structure as defined by claim 8 having a slide connected to and sliding along said base, the push rod being pivotally connected to the slide and the slide also having the spring means connected thereto, a pawl connected to the slide and extending forwardly therefrom, auxiliary spring means connected to the base and to a ratchet, said pawl and ratchet being adapted to cooperate to cause the auxiliary spring means to become operative to furnish additional pushing means to raise the table body.
11. In a table of the character indicated, a base, a cushion supporting top pivotally connected to said base, a slide operatively connected to the top and slidable on the base, a pawl pivotally connected to the slide and adapted to engage a notched bar, a notched bar slidably connected to the base and the slide, said bar being connected by means of springs to the base, said springs being put under tension by longitudinal motion of the bar away from the point of pivotal connection of the base and top, said pawl being adapted to engage the notches of said bar to cause movement thereof longitudinally of the frame, and means for varying the point at which the pawl will engage a notch of the notched bar so as to vary the amount of tension which will be exerted by the springs to cause lifting of the table.
12. A structure as defined by claim 11 in which the last named means is a bar slidably longitudinally of the base and has an angle to be engaged by the pawl, and said pawl has a projection engageable with said bar so that the pawl may be lifted out of engagement with the notched bar.
13. In a table of the character indicated, a cushion supporting frame, a cushion support rising therefrom and having a cushion pivotally connected thereto, a rack and pinion mechanism connecting said cushion and said support for adjusting the angular relation of the cushion with respect to the frame.
14. A structure as defined by claim 13 having latching means engaging the pinion to prevent relative movement of the rack and pinion, said latching means being slidable transversely of the rack into or out of engagement with the teeth of the pinion.
15. A structure as defined by claim 1 having latching means movable transversely to the rack and axially of the pinions to engage or disengage the teeth of said pinions to secure said pinions against rotation or release them for rotation, whereby to hold the cushions in adjusted positions with relation to the frame.
16. In a table for the purpose indicated, a base, a superstructure pivotally supported thereby, a cushion pivotally supported on the superstructure, pairs of pivotally connected links connecting opposite sides of the superstructure with the cushion to support the same in adjusted position, the pivotal connecting means for the links extending across the table and connecting the links upon opposite sides thereof, a U-shaped latch having notches in its arms to engage the said pivotal connecting means, the ends of the arms being pivotally connected with the cushion.
17. A table having a cushion supporting frame comprising a pair of substantially parallel longitudinally extending side members having slots in the portions facing each other and extending longitudinally of the side members, a cushion support having a part extending into said slots which serve as guiding means to assure a definite direction of movement of the cushion with relation to the frame, a longitudinally extending rack, a pinion associated therewith whereby to cause movement of the cushion longitudinally of the frame, and latching means movable axially of the pinion to engage or disengage the teeth of the pinion to hold the cushion in adjusted position.
18. A table of the character indicated comprising a rigid frame, a movable cushion carried thereby, rack and pinion connecting means connecting the frame and cushion, the rack being rigidly connected to the frame and extending longitudinally thereof so that the cushion may be adjusted longitudinally of the frame, and latching means to hold the rack and pinion in relatively adjusted positions whereby to hold the cushion in adjusted positions.

EDW. F. LUNDEEN. 50
